UNITED STATES PATENT OFFICE.

JOHN WEEKS, OF PECKHAM, COUNTY OF SURREY, ENGLAND.

UMBRELLA-FRAME.

SPECIFICATION forming part of Letters Patent No. 416,658, dated December 3, 1889.

Application filed November 15, 1888. Serial No. 290,908. (No model.)

To all whom it may concern:

Be it known that I, JOHN WEEKS, a subject of the Queen of Great Britain, and a resident of Peckham, in the county of Surrey, in England, have invented certain new and useful Improvements in Frames for Umbrellas and the Like, of which the following is a specification, reference being had to the accompanying drawings.

These improvements refer to the ribs and stretchers, and especially to the rib and stretcher joint of an umbrella-frame, and combine to make the frame more compact when folded, while at the same time the strength and lightness are increased.

In the accompanying drawings, Figure 1 is a side view of the improved form of rib at the stretcher-joint, and Fig. 2 a cross section. Fig. 3 shows the geat before being bent, and Fig. 4 after being bent into shape ready to be applied to the rib. Fig. 5 is a cross-section of the geat. Fig. 6 is a side view, and Fig. 7 a cross-section through the stretcher-joint after the geat has been applied and bent over and the rivet-holes made therein. Fig. 8 is a plan view of the stretcher. Fig. 9 is a side view, Fig. 10 a cross-section of the rib and stretcher joint, and Fig. 11 a cross-section through rib and stretcher folded. Fig. 12 is a side view (in continuation, though broken in length, of Fig. 9) of rib and stretcher at the place where the rib enters a notch in the runner-flange; and Fig. 13 is a cross-section through the rib at this place.

At the stretcher-joint of a U-shaped rib A, I turn over toward the inside and flatten down the sides of the rib, as shown at A', Figs. 1 and 2, and I form the geat B, Fig. 3, with two correspondingly-shaped lugs B' for containing the holes for the joint pin or rivet, so that when the geat is first bent into the shape shown in Figs. 4 and 5 and lapped around the rib at this place, and the lugs B' folded inward, as shown in Figs. 6 and 7, the lugs B' of the geat fill the hollow formed in each side of the rib by the aforesaid turning over and flattening down of the sides of same. The geat is thus prevented from shifting endwise along the rib; or, instead of turning down the rib in this place, I merely cut out half-round

notches therein; but this weakening of the rib might then not be compensated for sufficiently by the geat B.

If the rib, as shown at A², Fig. 1, is bulged and the geat perforated at this place, as shown at B², Figs. 3, 4, 5, 6, 9, and 10, and as described in my patent application filed in the United States Patent Office on the 31st May, 1887, Serial No. 239,863, then the joint is well down in the hollow of the rib without loss of strength to the joint, the rivet C not passing through the rib A, but through the geat B, and the stretcher and the rib fold closely into each other without protuberance at the joint, as shown at Figs. 9, 10, and 11. 65

In connection with the rib and geat formed as described I may use any stretcher with three-pronged rib-joint end, but by preference the solid three-pronged stretcher claimed in my aforesaid patent specification. This 70 form of stretcher is by preference made of ribbon metal folded into the required double-U section by rolling, but may also be made otherwise, such as by rolling out of the solid.

In Figs. 8, 9, 10, and 11 is shown a three-pronged stretcher made out of one piece of ribbon metal by rolling. 75

The rib where it lies in the notch formed in the edge of the runner-flange is, as shown at E, in Figs. 12 and 13, flattened down, so that 80 the ribs will lie deeper in the said notches and the umbrella when folded will present a less bulky appearance at this place.

I have herein described and shown a U-shaped rib provided with a bulge, and I do 85 not desire to claim this construction, broadly, herein, as it forms the subject-matter of claims in my application of patent hereinbefore referred to.

Having fully described my invention, what 90 I desire to claim and secure by Letters Patent is—

1. A trough-shaped umbrella-rib formed with a bulge A² at the stretcher-joint and having turned-down parts A' at that place, 95 substantially as set forth.

2. In combination with a trough-shaped umbrella-rib having turned-down stretcher-joint parts A', a geat B, with lugs B', which are turned down toward the inside to fill the 100

cavities at A' and are adapted to receive the rivet C, which passes through the geat, but not through the rib, substantially as set forth.

3. The geat B, with lugs B' B' and hole B², 5 in combination with a trough-shaped rib A, with turned-down parts A' and bulge A², substantially as set forth.

4. A trough-shaped umbrella-rib having turned-down stretcher-joint parts A' a geat 10 B, with turned-down lugs B' and rivet C, and the double-U-shaped three-pronged stretcher D, made of ribbon metal and having a three-pronged stretcher-joint end, substantially as set forth.

15 5. In an umbrella, the combination, with the runner, of a trough-shaped rib having its

sides bent inwardly and flattened down to form a recessed portion E, whereby the rib is brought closer to the runner without weakening such rib, substantially as and for the 20 purposes specified.

6. A trough-shaped umbrella-rib having turned-over parts E and A', and a geat B, with turned-down lugs B' and rivet C, in combination with a double-U-shaped stretcher 25 D, substantially as set forth.

JOHN WEEKS.
